United States Patent Office.

SAMUEL WOOLSTON, OF VINCENTOWN, NEW JERSEY.

Letters Patent No. 98,005, dated December 14, 1869.

IMPROVEMENT IN CAMELS FOR RAISING VESSELS.

The Schedule referred to in these Letters Patent and making part of the same

To all whom it may concern:

Be it known that I, SAMUEL WOOLSTON, of Vincentown, New Jersey, have invented certain new and useful Improvements in Marine Camels; and I hereby declare that the following is a full and exact description thereof, reference being had to the accompanying drawings, and the letters of reference marked thereon.

In the accompanying drawings—

Figure 1 is a top view of my improved camel.

Figure 2 is a side view of the same.

My invention consists, first, in making the camel in two parts, so hinged together as to be opened to receive a vessel, and then closed around the latter, and the two parts of the camel fastened rigidly together, so as to act like an inseparable camel; second, in certain central elevations; third, in a transverse beam for preventing the two halves of the camel from oscillating, when opened to receive the vessel.

In the construction of my camel, the two halves A are made separate, and connected by strong bolts and staples B, at four different points. Three of these bolts being withdrawn from the staples, the two halves of the camel are opened on the hinge formed by the fourth bolt and its staples, which are not separated.

To prevent the halves from oscillating upon each other when thus opened, a cross-beam, C, is employed, passing transversely through the elevations E of the camel.

After closing the camel upon the vessel, the bolts are all replaced in the staples, thus binding the two halves of the camel rigidly together.

In order to give greater room and strength to the staples and bolts, the central elevations E are employed, and these elevations also serve for the insertion of beam C, as above mentioned.

At each side of the well, a high truss-frame, D, is erected, for giving additional strength to the camel, and also for the attachment of ropes in suspending the vessel.

This camel may be used as a submarine elevator, or as a dry-dock.

Having described my invention,

I claim—

1. The arrangement of the camel in two parts, so hinged together as to be opened to receive the vessel, and then rigidly united like a single boat, substantially as set forth.

2. The central elevations E, substantially as set forth.

3. The cross-beam C, arranged substantially in the manner and for the purposes set forth.

SAMUEL WOOLSTON.
